UNITED STATES PATENT OFFICE.

JOHN FREDERICK MASSEY, OF CHICAGO, ILLINOIS.

WINDOW.

Application filed September 22, 1926. Serial No. 137,030.

My present invention relates to improvements in windows, and more particularly to windows of the sliding and swinging sash type.

5 One object of the invention is to provide a simple and efficient construction whereby the sashes may be turned over in the window frame, thus presenting the outer sides of the glasses inwardly, the arrangement being 10 such that in their turned over positions, the sashes are positioned entirely within the room.

Another object of the invention is to provide a window construction of the type mentioned which is simplified and improved in 15 its construction increasing its efficiency and enhancing its practicability and commercial value.

With these and other objects in view, 20 which will more fully appear as the nature of the invention is better understood, the invention consists in the combination, arrangement and construction of parts hereinafter described, pointed out in the appended 25 claims and illustrated in the accompanying drawings, it being understood that many changes may be made in the size and proportion of several parts and details of construction within the scope of the appended claims, 30 without departing from the spirit or sacrificing any of the advantages of the invention.

One of the many possible embodiments of 35 the invention is illustrated in the accompanying drawings, in which:—

Figure 1 is a vertical section of a window constructed in accordance with the present invention.

Figure 2 is a face view showing one of the 40 sashable and swingable members or sashes and the appurtenances thereof.

Figure 3 is an edge view of the same.

Figure 4 is an enlarged detail section 45 showing the manner in which the sashes are guided and detachably held against swinging in the frame.

Figure 5 is an enlarged detail vertical section illustrative of the manner in which the sashable and swingable hinge members of my 50 improvement are detachably connected to the side stiles of the frame, said section being taken on the line 5—5 of Figure 6.

Figure 6 is a detail view of the same, on a reduced scale, and taken from a view point 55 at the left of and right angles to Figure 5.

In the drawing the numeral 10 indicates a

window frame, which may be of any suitable construction provided with grooves 18 for upper and lower sashes, designated by the numerals 11 and 12, respectively. Each 60 sash is provided with two guides 14 in the form of strips, and two sashable and swingable hinge members 17. Each sash is supported through the medium of sash cords 15 which are fastened to the sashable and swingable hinge members 17 at intermediate points in the length of the latter. The said members 17 are pivotally connected to the edges of the sash at the points 16, Figures 2 and 3. The sash cords 15, shown as chains, are 65 passed over pulleys 15*, Figure 1, and are designed to be connected in conventional manner with weights for counterbalancing the sashes 11 and 12. The metal strip-like guides 14 slide in the grooves 18 of the frame 70 and hold the sashes in place, obviating the necessity of providing the customary guideways to receive the edges of the sash. Bolts 13 are attached to the metal guides 14 and extended through the sash bars to provide 75 means for withdrawing the strip-like guides 14 in the sashes laterally from the grooves 18 in the frame precedent to positioning the sashes as in Figure 1.

The operation of the window is as follows: 80 The lower and inner sash 11 is raised in the ordinary way to about six inches from the top of the frame and the members 17 of said sash are connected to the frame by means of latches or bolts 21, one of which is shown by 85 full lines in Figure 5 in operation.

The guides 14 are withdrawn laterally from grooves 18 in frame by means of the bolts 13, permitting the sash to be swung inward and turned on the pivots 16 so as to 90 present the outer side of the sash glass uppermost in the room, as shown in Figure 1.

The upper sash 12 is lowered in the ordinary way and its members 17 are connected to the frame by means of the latches 21. 100 Then after the guides 14 of the sash 12 are withdrawn laterally from their respective grooves 18, the said sash 12 is swung inwardly in the same manner as the lower sash. The sashes may be held at any angle while 105 washing them.

When the outer sides of the glasses have been cleaned the sashes are returned to their original positions by reversing the indicated operations. By this is meant, the latches 21 110 are disengaged from the members 17 complementary to the sashes, said latches being

swung to the idle dotted line position shown in Figure 5, and then when the sashes are restored to their sliding positions between and in parallelism with their respective 5 grooves 18, their strip-like guides 14 are moved laterally outward and hence into their respective grooves 18 so that the guides 14 rest partly in the sashes and partly in the grooves 18, Figure 4, to permit of rectilinear 10 or sliding movement of the sashes. The sash 12 is returned to its original position first.

The sashes characterized as stated do not 15 interfere with screens which may be attached to the frame in the ordinary way. The members 17 may be made any length desired to afford the sash position wanted when the sashes are adjusted as in Figure 1.

The lower sash 11 when positioned in 20 the upper part of frame may be lowered to any desired position by placing extra latches 21 for use in conjunction with the sash 11 wherever wanted.

One latch 21 is shown in Figure 5 as 25 holding one member 17, and it will be understood that said latch 21 is detachably secured against casual movement by means of a clip 22. This clip prevents casual movement of the latch 21, and yet when a 30 little stress is applied to the said latch 21, the latch may be disengaged from clip 22 and moved out of engagement with member 17, and then the latch 21 may be placed in the idle, out of the way, position shown 35 by dotted lines in Figure 5 in a pocket provided in frame 10.

Having described my invention, what I 40 claim and desire to secure by Letters Patent, is:

1. In combination, a frame having 45 grooves in the inner sides of its side stiles, sashes, guides carried by the sashes and movable into and out of said grooves, means connected to said guides and carried by the sashes for the projection and retraction of said guides, movable latches

carried by the side stiles of the frame, 50 slideable and swingable hinge members pivotally connected to the sashes and apertured for detachable connection to said latches, pulleys carried by the side stiles of the frame, and cords for the support of the sashes connected to said hinge members and passed over said pulleys.

2. In combination, a frame having 55 grooves in the inner sides of its side stiles, sashes, guides carried by the sashes and movable into and out of said grooves, means connected to said guides and carried by the sashes for the projection and retraction of said guides, movable latches 60 carried by the side stiles of the frame, slideable and swingable hinge members pivotally connected to the sashes and apertured for detachable connection to said latches, pulleys carried by the side stiles of the frame, and cords for the support of the sashes connected to said hinge members and passed over said pulleys; the said 65 side stiles of the frame being recessed, and the said latches being pivotally connected to the stiles and movable into and out of said recesses and being provided with angularly-disposed terminal portions, and the said stiles being equipped with clips to engage and detachably hold said terminal portions.

3. In combination, a frame having side 70 stiles and longitudinal grooves in the inner sides of said stiles, an element capable of 75 sliding and swinging movements relative to the frame, guides carried by and movable relative to said element and adapted to be projected into and retracted from said grooves, slideable and swingable hinge members 80 pivotally connected to the said element, means for detachably and pivotally connecting said hinge members to the side stiles of the frame, and means connected to said hinge members for supporting the 85 said element.

JOHN FREDERICK MASSEY.
